United States Patent Office

Des. 210,808
Patented Apr. 16, 1968

210,808

CONVERTIPLANE

Paul Julius Dancik, Broomall, Pa., assignor to The Boeing Company, Seattle, Wash., a corporation of Delaware

Filed Oct. 24, 1966, Ser. No. 4,381

Term of patent 14 years

(Cl. D71—1)

FIG. 1.

FIG. 2.

FIG. 3.

FIG. 4.

FIG. 5.

*Fig. 6.**Fig. 7.*FIGURE 1 is a top plan view of a convertiplane in flight mode embodying my new design;

FIGURE 2 is a front elevational view thereof;

FIGURE 3 is a side elevational view thereof;

FIGURE 4 is a plan view of the convertiplane with its wings and horizontal stabilizer in folded position;

FIGURE 5 is a front elevational view of the convertiplane shown in FIGURE 4;

FIGURE 6 is a side elevational view of the convertiplane shown in FIGURE 4; and

FIGURE 7 is a perspective view of the convertiplane shown in FIGURE 4.

I claim:

The ornamental design for a convertiplane, substantially as shown and described.
